UNITED STATES PATENT OFFICE

WILLIAM SHERMAN BROWN, OF KNOXVILLE, TENNESSEE, ASSIGNOR OF ONE-FOURTH
EACH TO K. W. DENNIS AND O. B. KEISTER, BOTH OF KNOXVILLE, TENNESSEE

VALVE GEAR

Application filed November 5, 1928. Serial No. 317,273.

This invention relates to valve gears for locomotives and the like, the general object of the invention being to provide means for giving the valve a quick movement at the beginning and end of the piston stroke and a slow movement of the valve when the same is in open position, whereby the full power of the steam is utilized on the piston so that the engine is operated with the maximum efficiency.

Another object of the invention is to make the gear mechanism on one side of the locomotive entirely independent of the mechanism on the other side whereby if any part of one mechanism should be damaged, the other mechanism would continue to operate and the construction of the mechanism is such that the use of eccentric mechanism is eliminated.

20 This invention also consists in certain other features of construction and in the combination and arrangement of the several parts, to be hereinafter fully described, illustrated in the accompanying drawings and 25 specifically pointed out in the appended claims.

In describing the invention in detail, reference will be had to the accompanying drawings wherein like characters denote like or 30 corresponding parts throughout the several views, and in which:

Figure 1 is a diagrammatic side view showing the mechanism at one side of a locomotive.

35 Figure 2 is a perspective view of the member which is connected with the main rod of the locomotive.

Figure 3 is a front view with parts broken away, showing the link, the hanger and a 40 part of the bracket for the hanger.

Figure 4 is a plan view of the link with its arms and trunnions and showing a part of the lever connected with the block of the link.

45 Figure 5 is a perspective view of the lever which communicates the movement of the main rod to the mechanism.

Figure 6 is a view of the bracket and hanger which communicates the movement of the mechanism to the valve.

In these views, A indicates a member formed with an offset end 1 which is bolted to the main rod 2 of the locomotive and this member A is formed with a rectangular central part 3 which forms a rectangular opening 55 for engaging a part on the pivot pin 4 which connects the front end of the main rod 2 to the cross head 5. The front end of the member A extends a considerable distance in front of the pivot pin, as shown, and this end is 60 pivoted to a vertically arranged lever 6, the upper end of which is formed with a slotted rectangular part 7. An arm 8 is pivoted to a bracket 9 fastened to the cylinder 10 of the locomotive and the other end of this arm is 65 pivoted to the lever 6 immediately below the part 7. This arm 8 forms a movable fulcrum for the lever 6.

A substantially U-shaped hanger 11 is pivotally supported at its upper ends to a pair 70 of ears carried by a bracket 12, the base part of which is slotted and bolted to a part 13 of the locomotive. This hanger is connected by a link 14 with the lever 6 a slight distance 75 below the fulcrum point of said lever. A slotted link 15 of arcuate shape is provided with the forwardly extending arms 16 at substantially its center, the arms having offset rear extensions which are formed with the trunnions 17 which engage bearing openings 80 formed in the limbs of the hanger 11 so that the link is pivotally connected with the hanger a distance below the upper ends of the limbs of the hanger, the extremities of these limbs forming the trunnions 18 which engage 85 the bearing holes in the ears of the bracket 12. The trunnions 17 are spaced from the link 15 so that the block 19, which is slidably mounted in the slot of the link, can move 90 from one end of the slot to the other without interference from the arms or their trunnions.

The front ends of the arms are pivoted to a block 20 which is slidably mounted in the slot in the part 7 of lever 6 and the block 19 is 95 pivoted to the forked end of a lever 21, the other end of which is pivoted to the outer part of a hanger 22 supported by a bracket 23 attached to a part of the locomotive and the inner part of the hanger has pivoted 100

thereto an end of a rod 24 which is keyed to the stem 25 of the valve 26, as shown at 27. The hanger 22 is of the shape shown in Figure 6, so that the rod 24 is spaced inwardly 5 from the member 21 and said rod passes through the slot in the base of the bracket 12. A link 28 connects the forward part of the member 21 with the bell crank 29 which in turn is connected by a link 30 with the reversing lever 31 of the locomotive.

From the foregoing it will be seen that the movement of the main rod 2 is communicated to the hanger 11 and link 15 through the lever 6 and its connections with these parts 11 and 15 and this movement of said parts 11 and 15 acts to reciprocate the valve 26 through the rod 24 through means of the member 21 and the hanger 22 and the extent of movement imparted to the valve and the parts 21 and 24 can be regulated from the lever 31 by changing the position of the block 19 in the link 15. Of course, it will be understood that the locomotive can be reversed by moving the block 19 into the upper part of the link 15.

By properly arranging the fulcrum member 8 in relation to the lever 6, angularity of said lever will be taken care of on extreme forward and backward movement of the cross head of the engine. As will be seen, the entire valve gear is outside of the vertical plane of the cross head and above the member A, but the valve rod 24 is arranged between the valve mechanism and the side of the locomotive so that it will be in alignment with the valve and its stem.

It will, of course, be understood that the mechanism at one side of the locomotive is the same as that on the opposite side. As before stated, this improved valve gear will increase the efficiency of the locomotive as it will give the valve a quick movement at the ends of the piston stroke and will retard the movement of the valve when the inlet port 40 is opened so that the piston will receive the full effect of the steam pressure. It will also be seen that the mechanism at one side of the locomotive is entirely independent of the mechanism on the other side and the use of 45 eccentric mechanism is eliminated.

It is thought from the foregoing description that the advantages and novel features of the invention will be readily apparent.

It is to be understood that changes may be 55 made in the construction and in the combination and arrangement of the several parts, provided with such changes fall within the scope of the appended claims.

What I claim is:—

60 1. A valve gear for a locomotive comprising a support, a hanger pivoted thereto, a link pivotally supported by the hanger, a bracket, a hanger pivotally supported thereby, means for connecting the second hanger 65 with the valve, a block in the link, a member

having one end connected with the block and its other end connected with the second hanger, a lever, a movable fulcrum for the same, means for connecting the lever with the main rod of the locomotive, means for communicating the movement of the lever to the link and the first hanger and means for manually adjusting the block in the link. 70

2. A valve gear for a locomotive comprising an upright lever, a movable fulcrum for the same, means for connecting the lower end of the lever with the front end of the main rod of the locomotive, a bracket supported on a part of the locomotive, a hanger pivotally connected with the bracket, a link 75 connecting the lower end of the hanger with the lever below the fulcrum point thereof, a slotted link pivotally supported in the hanger and having a forwardly extending part, means for slidably and pivotally connecting the said part with the upper end of the lever, a block in the slotted link, a second bracket, a hanger pivoted therein, a member pivoted at one end to the second hanger and having its other end pivoted to the block, 80 means for moving said member and block by the reversing lever and a rod connected with the second hanger and with the stem of the valve. 85

3. A valve gear for a locomotive comprising a member attached to the front end of the main rod of the locomotive, an upright lever having its lower end pivoted to the front end of said member, a movable fulcrum for the upper part of the lever, the 90 upper end of the lever above the fulcrum having a slotted enlargement, a bracket connected with a part of the locomotive, a hanger pivoted to the bracket, a link connecting the lower end of the hanger with the lever below the fulcrum point thereof, a slotted link having its intermediate portion pivoted in the hanger, forwardly extending arms connected with an intermediate portion of the slotted link, a block in the slot of the 95 enlargement of the lever to which the arms are pivoted, a block in the slot of the link, a lever having its front end pivoted to the block, a second bracket, a hanger pivoted thereto, said last mentioned lever being pivoted to the lower end of the hanger, a rod 100 pivoted to the hanger and connected with the stem of the valve and means for connecting the forward part of the second lever with the reversing lever of the locomotive. 105

4. A valve gear for a locomotive comprising a bracket fastened to a cylinder of a locomotive, a fulcrum member pivoted to the bracket, a vertically arranged lever pivoted to the fulcrum member adjacent the upper end of the lever, said upper end of the lever having an enlargement provided with a horizontal slot, a member connected with the forward end of the main rod of the locomotive and pivoted to the lower end of the lever, 110 115 120

said member having an opening therein for engaging a part on the pin which pivots the main rod to the cross head, a bracket attached to a part of the locomotive, a hanger pivoted to the bracket, a link connecting the lower end of the hanger with the lever below the fulcrum point of the lever, a slotted link pivoted in the hanger and having a forwardly extending part, a block pivoted to the said part and slidably mounted in the horizontal slot of the lever, a block in the slot of the link, a second bracket, a hanger pivotally supported thereby, a member connecting the lower end of the hanger with the block, a rod connecting the lower end of the hanger with the stem of the valve, said member being connected with the outer side of the hanger and the rod being connected with the inner side thereof and means for connecting the forward part of said member with the reversing lever of the locomotive whereby said member and block can be adjusted in relation to the slotted link.

In testimony whereof I affix my signature.

25 WILLIAM SHERMAN BROWN.
